UNITED STATES PATENT OFFICE.

CHARLES TWEEDIE, OF JEFFERSON CITY, MISSOURI.

DESIGN FOR A BOOT TOP.

Application filed July 8, 1922. Serial No. 3,000. Term of patent 7 years.

To all whom it may concern:

Be it known that I, CHARLES TWEEDIE, a citizen of the United States, and a resident of Jefferson City, county of Cole, and State of Missouri, have invented a new, original, and ornamental Design for a Boot Top, of which the following is a specification.

In the accompanying drawing, which forms part of this specification,

The figure is a perspective view of a boot

top embodying the design, the boot top being shown in position on a shoe which is indicated in dotted lines.

The cuff is preferably of material that contrasts with the body of the boot top.

I claim:—

The ornamental design for a boot top, as shown.

CHARLES TWEEDIE.
